(57) **CLAIM**

I claim, the ornamental design for high frequency coil for magnetic resonance image device, as shown and described.

DESCRIPTION

FIG. 1 is a front perspective view of high frequency coil for magnetic resonance image device showing my new design; FIG. 2 is a front view thereof; FIG. 3 is a rear view thereof; FIG. 4 is a side view thereof; FIG. 5 is a side view thereof; FIG. 6 is a top plan view thereof; and, FIG. 7 is a bottom plan view thereof.

The broken lines are for environmental purposes only and form no part of the claimed design.
